BOOK-SHELF UNIT OR SIMILAR ARTICLE

Thomas W. Tisdall and Calvin E. Brown, Altavista, Va.,
assignors to The Lane Company, Inc., Altavista, Va.,
a corporation of Virginia

Filed Nov. 4, 1966, Ser. No. 4,548

Term of patent 14 years

(Cl. D33—2)

The figure is a perspective view from the front and somewhat to the left side of the book-shelf unit or similar article of our new design.

The view from a diagonally opposite perspective is substantially identical.

We claim:

The ornamental design for a book-shelf unit or similar article, as shown and described.
